UNITED STATES PATENT OFFICE

2,691,960

CRAYON SHARPENER

Walter Albert Leeds and Norbert J. Sweete,
Chicago, Ill.

Application February 23, 1952, Serial No. 273,062

2 Claims. (Cl. 120—93)

1

This invention pertains to devices for sharpening or pointing the ends of crayons.

It is well known that due to the composition of crayons, the matter of sharpening or pointing by usual means and methods presents a somewhat awkward and messy task. The shaved particles have a tendency to cling to the cutting implement employed and the small shavings are difficult to confine or accumulate for proper disposal and, further, the hands of the person performing the operation become soiled.

One of the objects of our invention is to provide a novel crayon sharpener that is simple in construction, easy to use, and which obviates the foregoing difficulties.

Another object is to provide an improved crayon sharpener having a plurality of circumferentially spaced-apart cutter blades, arranged in converging relation to each other, for receiving the end of a crayon therein, with each blade having an inwardly facing cutting edge, together with relief portions adjacent said cutting edge to reduce the possibility of adherence of crayon shavings thereto.

A further object is to provide an improved crayon sharpener characterized by the provision of a cutter head and cutter blades, together with a shavings collector receptacle adapted to be detachably connected to the head in surrounding relation to the cutter blades.

Still another object is to provide an improved crayon sharpener having a cutter head formed with a guide opening, with the wall of the opening being of substantial length, together with a plurality of converging cutter blades connected to the head and disposed in registration with the guide opening.

Other objects and advantages of this invention will be apparent from the following description, taken in connection with the accompanying drawings, in which:

Figure 1 is a view, part in section and part in elevation, showing the crayon sharpener and shavings collector receptacle embodying the present invention.

Figure 2 is a plan view of the assembly of the crayon sharpener and shavings collector receptacle.

Figure 3 is a transverse sectional view, taken substantially as indicated at line 3—3 on Figure 1.

Figure 4 is an enlarged, fragmentary, axial section through the combined sharpener and shavings collector receptacle, taken substantially as indicated at line 4—4 on Figure 2.

Figure 5 is an enlarged, transverse, sectional

2

view, taken substantially as indicated at line 5—5 on Figure 4.

The crayon sharpener embodying the present invention comprises a unitary device indicated at 10, preferably molded from any suitable material such as, by way of example and not limitation, thermo-plastic material, such as polystyrene. Associated with the unitary sharpener device, in detachably connectable relation, is a shavings collector receptacle 11, which likewise may be formed as a unitary molded product of any suitable material, such as thermo-plastic material.

As shown in the drawing, the unitary sharpener device 10 comprises a head member or plate 12, formed with an opening 14, for the reception of the end of a crayon, as indicated at 15. Surrounding said opening, on the underside of said head member, is a flange or collar 16, which, together with the thickness of the head member 12, provides a guide wall of substantial length for insuring proper guidance for the end of the crayon when it is being inserted into the sharpener device preparatory to pointing or sharpening said crayon. The sharpening device 10 is provided with a plurality, herein shown as four, circumferentially spaced-apart cutter blades 18, which converge together in a direction away from the head plate 12, as clearly seen in Figures 1 and 4 of the drawing. The inner edge of each of the cutter blades is formed to provide a knife edge or cutting edge, as indicated at 19. The sides of the cutter blades taper toward the cutting edge and thereby provide relief portions for the shavings cut from the end of the crayon as the crayon is rotated in contact with the converging cutting edges 19 of said blades. Due to the shape of the cutter blades in cross section, as may be seen in Figure 5 of the drawing, relief is provided for such shavings when the crayon is rotated in either direction with respect to the cutter blades. By this arrangement, the shavings cut from the crayon tend to freely dislodge themselves from the cutter blades.

As herein shown, the upper ends of the cutter blades are formed integrally with the underside of the head plate 12 and the flange 16 thereof, and the lower or opposite ends of the cutter blades are preferably, but not necessarily, integrally connected together by a disk-like member indicated at 21.

The shavings collector receptacle 11 may be of any desired contour and, as shown, is of circular cross section. Said receptacle is closed at one end and the opposite or open end is provided with an internal annular recess 23, dimensioned

for a snug friction fit around an annular shoulder 25, formed on the underside of the head plate 12, as clearly seen in Figure 4 of the drawing. By virtue of this construction, the shavings cut from the crayons are conveniently collected within the receptacle and when desired the receptacle may be quickly and easily detached from the unitary cutter device 10 for disposal of the shavings therefrom.

It will be apparent that, if desired, the cutter device 10 may be utilized independently of a shavings collector receptacle.

Although we have herein shown and described a preferred embodiment of our invention, manifestly it is capable of modification without departing from the spirit and scope thereof. We do not, therefore, wish to be understood as limiting this invention to the precise embodiment herein disclosed, except as we may be so limited by the appended claims.

We claim as our invention:

1. A unitary, molded crayon sharpener formed of thermo-plastic material comprising a head member provided with an opening for the reception of a crayon therein, and a plurality of 25 circumferentially spaced-apart cutter blades secured at one end to the underside of said head member, in surrounding relation to said opening, said cutter blades having cutting edges extending toward the axis of said opening and in converging relation to each other, in a direction

away from said head member, the ends of said blades, remote from said head, being rigidly connected together.

5 2. A unitary, molded crayon sharpener formed of thermo-plastic material comprising a head member provided with an opening for the reception of a crayon therein, a plurality of circumferentially spaced-apart cutter blades secured at one end to the underside of said head member, in surrounding relation to said opening, said cutter blades having cutting edges extending toward the axis of said opening and in converging relation to each other, in a direction away from said head member, the ends of said blades, 15 remote from said head, being rigidly connected together, and a collar surrounding said opening and constituting a guide for centering the crayon with respect to said cutter blades.
